UNITED STATES PATENT OFFICE.

DAVID HEALD, OF MILFORD, NEW HAMPSHIRE.

DESIGN FOR RAILS FOR HAT-RACKS.

Specification forming part of Design No. 5,968, dated July 2, 1872.

To all persons to whom these presents shall come:

Be it known that I, DAVID HEALD, of Milford, in the county of Hillsborough and State of New Hampshire, have invented a new and Improved Design for Rails of Hat-Rack; and that the following description, taken in connection with accompanying plate of drawing, is a full and exact specification of the same.

The design embraced herein is illustrated in the accompanying plate of drawing, the several figures of which are front views, showing hat-racks of various shapes in its outline or border, but each embracing the feature of the present design.

The hat-rack is composed of crossing-rails

A that, from end to end, have a corresponding and regular sinuous or serpentine form, leaving or producing oval or elliptical shaped openings B.

Having thus described my invention, what I claim, and desire to secure by Letters Patent, is—

The design and form of the bars or rails A for hat-racks, substantially as herein shown and described.

DAVID HEALD.
